UNITED STATES PATENT OFFICE.

A. ADGATE DUER, OF BALTIMORE, MARYLAND.

CASTER.

SPECIFICATION forming part of Letters Patent No. 242,820, dated June 14, 1881.

Application filed September 21, 1880. (Model.)

To all whom it may concern:

Be it known that I, A. ADGATE DUER, of Baltimore city, State of Maryland, have invented certain new and useful Improvements 5 in the Manufacture of Casters; and I hereby declare the same to be fully, clearly, and exactly described as follows, reference being had to the accompanying drawings, in which—

Figure 1 is a side elevation of the device. 10 Fig. 2 is a sectional view, and Fig. 3 is a top-plan view, of the same.

My invention has reference to furniture-casters; and it consists in a method of constructing the caster embodying certain improvements 15 on that employed in making the caster for which Letters Patent of the United States No. 229,033 were granted me June 22, 1880. In the said device the socket and flange were cast integral upon the headed center pin, which 20 was previously thrust through the yoke. This mode of constructing the caster, while resulting in the production of a thoroughly satisfactory article, was somewhat expensive, as considerable care was requisite in centering 25 the pins in the molds.

The object of my present invention is to avoid this cost and furnish a caster equal in all respects, so far as merit is concerned, to the patented device.

30 In the accompanying drawings, A is the socket, and E the flange, cast in one piece, as shown. The socket is furnished with a thread, a, and at the top is formed a transverse groove, d.

35 B is the yoke, between the arms of which the roller C is mounted, as usual, on a pivot-pin, b.

The center pin, D, is a machine-made rivet, on which is formed a head, e, the pin being 40 of a size to fit closely in the socket A.

In putting the parts together the pin D is passed through the hole in the yoke B, and is then driven through the socket A. The pro-

jecting end D' is then secured by a blow upon a riveting-steel, which rests upon the end or 45 head D' in the line of the groove d. By this means an indentation, f, is formed, which causes the end to bulge laterally and secures the pin rigidly in the socket. The part D'' of the pin D is enlarged, as shown, obviating all 50 danger of jamming the yoke in the act of riveting the pin.

It will thus be seen that, aside from the riveting of the pivot b, the hand-labor involved in constructing the caster is confined to a single 55 blow on the end of the pin D, far less than was required to center the pins in the molds in constructing the patented device hereinbefore referred to, and a great saving in time 60 results.

Instead of heading the pin above the socket, the bore of the latter may be slightly contracted, so that the pins are rigidly secured 65 therein in the act of driving them home. In this case the bore may extend wholly or but partly through the socket.

It will be understood that the described mode of constructing the device leaves nothing to be desired in point of economy. The pins or rivets are staple articles of commerce, and the 70 remaining parts may be cheaply cast.

What I claim as new, and desire to secure by Letters Patent, is—

The method herein described of constructing 75 casters, consisting in casting a socket and flange integral and providing a shouldered and headed center pin or pivot, and combining the said parts and the yoke by passing the pivot-pin through the yoke and into the socket, with its shoulder abutting against the under side of 80 the flange, and then riveting the pin and socket rigidly together, as set forth.

A. ADGATE DUER.
